UNITED STATES PATENT OFFICE

91,347

DESIGN FOR A ROLLING PIN CONTAINER

Robert Esterly Boyce, Chester, W. Va.

Application November 4, 1933. Serial No. 49,652

Term of patent 3½ years

To all whom it may concern:

Be it known that I, ROBERT ESTERLY BOYCE, a citizen of the United States, residing at Chester, in the county of Hancock and State of West Virginia, have invented a new, original, and ornamental Design for a Rolling Pin Container, of which the following is a specification, reference being had to the accompanying drawing, forming part thereof.

Figure 1 is a side elevational view of a rolling

pin container, showing my new design.

Figure 2 is a top plan view thereof.

Figure 3 is an end elevational view thereof.

I claim:—

The ornamental design for a rolling pin container as shown.

ROBERT ESTERLY BOYCE.
